UNITED STATES PATENT OFFICE

2,098,924

REFRIGERATING APPARATUS

Edward B. Newill, Dayton, Ohio, assignor to General Motors Corporation, Dayton, Ohio, a corporation of Delaware

Application May 27, 1936, Serial No. 82,098

6 Claims. (Cl. 62—108.5)

This invention relates to refrigeration and particularly to trays adapted to have water frozen therein.

An object of my invention is to remove ice from a tray without applying heat to the tray.

Another object of my invention is to provide an improved device for removing ice from a tray.

A further object of my invention is to provide a device for removing a plurality of ice blocks together with a grid from a tray, which device includes a portion embedded in at least one of the ice blocks.

In carrying out the foregoing objects, it is a still further and more specific object of my invention to provide a device for removing ice together with a grid, which comprises at least two longitudinal and a plurality of transverse partitions for dividing the interior of a tray into a plurality of rows of ice blocks, from a tray and which device includes a portion embedded in the end ice block located between two of the longitudinal partitions of the grid.

Further objects and advantages of the present invention will be apparent from the following description, reference being had to the accompanying drawings wherein a preferred form of the present invention is clearly shown.

In the drawings:

Fig. 1 is a top plan view of an ice tray showing an ice removing device constructed in accordance with the present invention associated therewith;

Fig. 2 is a vertical section through the tray taken on the line 2—2 of Fig. 1;

Fig. 3 is a view similar to Fig. 2 showing the ice within the tray after being partially removed therefrom by the removing device;

Fig. 4 is a vertical sectional view through the tray and ice removing device and is taken on the line 4—4 of Fig. 2;

Fig. 5 is a fragmentary top plan view of a modified form of the device of the present invention; and

Fig. 6 is a vertical sectional view of the device disclosed in Fig. 5 taken on the line 6—6 thereof.

Referring to the drawings for a detailed description of my invention, I have shown in Fig. 1 thereof an ice tray generally represented by the reference character 10. The tray 10 has side walls 11 and end walls 12 which extend outwardly from the bottom to the top of the tray. Tray 10 has its top edge rolled over as at 13 to stiffen or make the tray rigid. A unitary grid structure 14 is disposed within tray 10 for dividing the interior thereof into a plurality of open top molds or

compartments 15. The grid 14 includes two spaced apart vertically disposed longitudinally extending partitioning members or portions 16 and a plurality of vertically disposed transverse partitioning members or portions 17 integrally 5 united with an inter-secting the longitudinal partitions to form three rows of the molds or compartments 15. It will be noted (see Figs. 2, 3 and 4) that the one end wall 12 of tray 10 slants upwardly at a greater angle than the other end 10 wall and the side walls 11 thereof for a purpose to be hereinafter described. The said one end wall 12 of tray 10 has a heavy metal piece 19 secured in any suitable manner, such as by being welded thereto. The heavy metal piece 19 fits under the 15 rolled over top edge 13 of tray 10 to protect this edge from being damaged and is provided with a cut or notched-out groove or the like 21. This groove 21 is adapted to receive a finger portion 22 of a lever, generally represented by the reference character 23, having a handle portion 24 and an intermediate body portion 25. A lug 26 formed on lever 23, between the body portion 25 and the handle portion 24 thereof, extends downwardly 20 and rests upon the top of one of the transverse 25 partitions 17 of grid 14 to maintain all portions of lever 23 above water or ice contained in the tray 10. An aperture 28 provided in the body portion 25 of lever 23 has a shaft 29, provided with a head 31, extending therethrough. An elongated 30 horizontally extending plug 32 is threaded upon or otherwise secured to the lower end of shaft 29. The head 31 formed on the upper end of shaft 29 and the plug 32 prevents the shaft from being separated from lever 23. It will be noted 35 that the plug 32 extends into the compartment 15 at the one end of tray 10 located intermediate the two longitudinal partitions 16 of the grid structure 14. Normally, the plug 32 is preferably positioned intermediate the top and bottom of 40 compartment 15. The tray 10 is disclosed as having ice blocks 34 formed in the plurality of compartments 15 and with the plug 32 embedded in the intermediate end blocks 34. The purpose 45 of lever 23 and its associated parts will now be described.

Referring to Fig. 2 of the drawings, it will be noted that the lever 23 is in its normal position with lug 26 resting upon grid 14 and with the plug 32 embedded slightly below the center of the 50 intermediate end ice block 34. The block of ice 34 having plug 32 embedded therein is surrounded on three sides by the walls 17 and wall 16 of the grid structure 14. This ice block contacts walls of tray 10 only along the bottom and 55

one side thereof. Obviously, therefore, this particular ice block has more walls thereof bonded to the grid 14 than other blocks of ice around the upright walls of tray 10 and will adhere more 5 strongly to the grid structure than these other ice blocks. This inherent characteristic of a tray and grid structure of the type disclosed is utilized in the present invention to remove all the ice blocks 34 together with the grid structure 10 from tray 10 to thus eliminate the necessity of applying heat to the tray to release the ice therefrom. Therefore, when force is applied to handle portion 24 of lever 23, the lever pivots about a pivot, groove or notch 21, exteriorly of 10 tray 10. Movement of handle 24 upwardly relative to tray 10 raises lever 23 and the lever pulls shaft 29, plug 32 and the ice blocks 34 together with the grid 14 upwardly and outwardly of tray 10. It will be noted that the slant of the one end 15 wall 12 of tray 10 affords space between the end ice blocks 34 and the tray wall for elevating the grid and ice blocks bonded thereto upwardly of the tray. Since the one end wall 12 of tray 10 converges outwardly a greater distance than 20 other upright walls thereof, it is inherent in the structure disclosed for this end wall to be moved outwardly away from the ice blocks 34 when force is applied to lever 23. A force applied to lever 23 at the point of its pivotal engagement with the 25 converging end wall 12 will cause a flexing movement of this end wall relative to the ice in the tray to thereby substantially peel the wall away from the ice. The flexing of the outwardly converged tray end wall also causes a slight movement 30 of other walls of the tray relative to the ice and thus initially breaks the ice bond between the ice and these other walls to thereby facilitate removal of the ice together with the grid structure 14 from the tray upon manipulating lever 23.

After the grid 14 together with ice blocks 34 adhering thereto have been removed from tray 10, the ice blocks may be removed from grid 14 in any suitable or desirable manner. While my 45 invention relates primarily to the feature of removing a grid together with ice blocks bonded or adhering thereto from a tray, it will be understood that the grid may be of any suitable or desirable construction to facilitate release of ice 50 blocks therefrom after the grid has been removed from the tray. For example, the grid may be constructed in accordance with the teaching contained in the patents to Jules N. Saler No. 2,037,517, No. 2,037,518, No. 2,037,519 and No. 55 2,037,521 of April 14, 1936 so as to provide quick removal of ice blocks therefrom after having been removed from the tray in accordance with the present invention.

Upon again utilizing the tray 10 of my invention for freezing water or other liquids, the lever 60 23 together with shaft 29 and plug 32 carried by the lever are placed in the associated position with tray 10 as shown in Fig. 2 of the drawings, so that plug 32 will be submerged in water contained in the tray prior to placing the tray on a support of a cooling element or evaporator of a refrigerating apparatus preferably of the household type. Obviously, my improved grid and ice removing device can be used over and over again 65 without damage to the tray by virtue of the reinforcing member or block 19 being secured to the end of the tray to which the leverage or camming force is applied.

Referring now to Figs. 5 and 6 of the drawings 70 75 wherein I have disclosed a modified form of the

invention, it will be noted that a portion of the rolled-over top edge 13a of tray 10a is cut away along the slanting end wall 12a thereof. This cut-away portion of the top edge 13a of tray 10a is occupied by a rigid relatively thick metal member 19a which is secured to tray 10a by rivets 36 5 (see Fig. 6) or by being welded to the tray end wall 12a. Member 19a is provided with a pair of spaced apart upstanding ears 37 (see Fig. 5) through which a rod or pin 38 passes. Rod 38 10 passes through an opening 39 provided in a lever 41 and forms a pivot point for the lever. Lever 41 includes a handle portion 42 and a finger end portion 43. A plug 44 secured to a shaft 45 is embedded in the intermediate end 15 ice block 34a within tray 10a. The shaft 45 includes a hooked or bent-over upper end 46 which fits in and engages the hollowed-out part of finger 43 of lever 41. An upstanding edge portion 47 (see Fig. 6) formed on the rigid reinforcing member 19a forms a stop for the fingered end 43 of lever 41 to prevent this end of the lever together with the shaft 45 and the plug 44 from lowering beyond a predetermined point within the intermediate end ice compartment 15a.

After water has been frozen in tray 10a to embed plug 44 within the intermediate end ice block 34a, a downward force applied to the handle end 42 of lever 41 will cause movement of the lever about the pivot rod 38 to elevate the finger end 43 thereof. Elevation of the finger end 43 of lever 41 causes the plug 44 together with the ice blocks 34a and grid 14a to move upwardly of tray 10a so as to release ice from the tray in a manner similar to that described in the showing of the device disclosed in Figs. 1 to 4 inclusive.

From the foregoing, it will be seen that I have provided novel and improved devices for removing a grid structure together with ice blocks bonded or adhering thereto from a tray, which devices are inexpensive and effective in their function. The improved devices disclosed remove all ice blocks from a tray without causing the blocks to chip or crack into small pieces and in addition permit removal of the ice blocks from the tray without applying heat to the tray. Thus, ice blocks produced in the trays of the present invention retain latent heat stored therein and are, therefore, more efficient in cooling drinks, etc.

While the forms of embodiments of the invention as herein disclosed constitute preferred forms, it is to be understood that other forms might be adopted, all coming within the scope of the claims which follow.

What is claimed is as follows:

1. In combination, a relatively shallow tray of the type adapted to be inserted in or placed on a cooling element of a household refrigerating apparatus and adapted to contain a substance to be frozen, a unitary grid structure within said tray dividing the interior thereof into a plurality of molds, a member embedded in the frozen substance within one of said molds and having a portion thereof extending outwardly therefrom, means for removing the frozen substance together with said grid structure from said tray, said means including a lever having a handle portion and an end portion pivotally engaging a portion of said tray, said lever having a portion intermediate the handle and said end portions thereof attached to said extending portion of said member, and said lever being adapted when moved about its pivotal engagement with said 75

tray to pry said grid structure and the frozen substance from the tray.

2. In combination, a relatively shallow tray of the type adapted to be inserted in or placed on a cooling element of a household refrigerating apparatus and adapted to contain a substance to be frozen, a unitary grid structure within said tray dividing the interior thereof into a plurality of molds, a member embedded in the frozen substance within one of said molds and having a portion thereof extending outwardly therefrom, means for removing the frozen substance together with said grid structure from said tray, said means including a lever having a handle portion and an end portion engaging said extending portion of said member, said lever having a portion intermediate the handle and said end portions pivotally attached to said tray, and said lever being adapted when moved about its pivotal attachment to said tray to pry said grid structure and the frozen substance from the tray.

3. In combination, a relatively shallow tray of the type adapted to be inserted in or placed on a cooling element of a household refrigerating apparatus and adapted to contain a substance to be frozen, a unitary grid structure within said tray, said grid structure comprising vertically disposed spaced apart longitudinally extending partitions and a plurality of vertically disposed transverse partitions intersecting said longitudinally extending partitions, said grid dividing the interior of said tray into three rows of molds, a member embedded in the frozen substance within the end mold of the central row thereof and having a portion extending outwardly from the frozen substance, means for removing the frozen substance together with said unitary grid structure from said tray, said means including a lever having a handle portion and an end portion pivotally engaging a portion of said tray, said lever having a portion intermediate the handle and said end portions thereof attached to said extending portion of said member, and said lever being adapted when moved about its pivotal engagement with said tray to pry said grid structure and the frozen substance from the tray.

4. In combination, a relatively shallow tray of the type adapted to be inserted in or placed on a cooling element of a household refrigerating apparatus and adapted to contain a substance to be frozen, a unitary grid structure within said tray, said grid structure comprising vertically disposed spaced apart longitudinally extending partitions and a plurality of vertically disposed transverse partitions intersecting said longitudinally extending partitions, said grid dividing the interior of said tray into a plurality of rows of molds, said molds including end corner molds bounded on two sides by the partitions of said grid structure and an intermediate end mold bounded on three sides by the partitions of said grid structure, a member embedded in the frozen substance within the intermediate end mold of the plurality of molds and having a portion extending outwardly from the frozen substance,

means for removing the frozen substance together with said grid structure from the tray, said means including a lever having a handle portion and an end portion engaging said extending portion of said member, said lever having a portion intermediate the handle and said end portions pivotally attached to said tray, and said lever being adapted when moved about its pivotal attachment to said tray to pry said grid structure and the frozen substance from the tray.

5. In combination, a tray of the type adapted to be placed on or inserted in a cooling element of a household refrigerating apparatus and adapted to contain a substance to be frozen, said tray having one end wall thereof directed outwardly toward the top of the tray a greater distance than other walls thereof, a unitary grid structure within the tray, said grid structure including vertically disposed spaced apart longitudinally extending partitions and a plurality of vertically disposed transverse partitions intersecting said longitudinal partitions, said grid dividing the interior of said tray into a plurality of rows of molds, said molds including end corner molds bounded on two sides by the partitions of said grid structure and an intermediate end mold bounded on three sides by the partitions of said grid structure, a member embedded in the frozen substance within the intermediate end mold of the plurality of end molds and having a portion extending outwardly from the frozen substance, means for removing the grid structure together with the frozen substance from the tray, said means including a lever attached to said extending portion of said member and pivotally engaging the wall of said tray directed outwardly a greater distance than other walls thereof, and said lever being adapted upon movement thereof about said pivotal engagement with said tray to pry the entire grid structure and the frozen substance from the tray.

6. In combination, a relatively shallow tray member of the type adapted to be inserted in or placed on a cooling element of a household refrigerating apparatus and adapted to contain a substance to be frozen, said tray member having an upright wall portion directed outwardly toward the top thereof, a unitary grid structure within said tray member dividing the interior thereof into a plurality of molds, a member embedded in the frozen substance within one of said molds and having a portion thereof extending outwardly from the frozen substance therein, means for removing said grid structure together with the frozen substance from the tray member, said means comprising a lever having a part thereof attached to said portion of one of said members and another part thereof adapted to engage said portion of the other of said members, and said lever being adapted upon movement thereof to flex the tray member and pry the grid structure and frozen substance adhering thereto from the tray member.
